GASEOUS ELECTRIC DISCHARGE DEVICE

Marcello Pirani, Berlin-Wilmersdorf, and Hans Ewest, Berlin, Germany, assignors to General Electric Company, a corporation of New York

Application February 9, 1931, Serial No. 514,670
In Germany February 18, 1930

1 Claim. (Cl. 176—14)

The present invention relates to gaseous electric discharge devices generally and more particularly the invention relates to such devices in which electron emitting bodies, heated to a red heat, or to incandescence by the operating current of the device, are used as the electrodes of the device.

Hitherto it has been the practice to provide the electrode chambers of such devices with a light impervious covering, utilizing only the light emitted by the positive discharge column of the device. The object of this invention is to make available for the arts generally and particularly for use in signs a part of the light emitted by the gaseous electric discharge devices.

In accordance with this object an opaque covering having a window in the vicinity of the electrodes is utilized to permit the passage of part of the light emitted by said electrodes. The window may be of any suitable shape though we prefer one of round shape so that it forms a brilliant point light source in contrast to the linear shaped light source of the positive column, this being desirable to attract the attention of an observer as for example in the use of such electric discharge device to designate an exclamation point in sign structures. In this latter case the electric discharge device is mounted vertically, the top electrode chamber being totally covered and the covering of the bottom electrode chamber having a round window in the vicinity of the heated electrode.

In the drawing an embodiment of the invention is shown in elevation, part of the electrode chambers being cut away to show the structure thereof.

Referring to the drawing the electric discharge device comprises a tube 1 filled with a luminous gas, such as neon, helium, argon, alone or in combination with mercury, surrounding the positive column discharge path, electrode chambers 2 being located at the ends of said tube 1. Electron emitting electrodes 3 are sealed into said chambers 2, said electrodes 3 being heated to an electron emitting temperature for the start of the electric discharge device and being maintained at a glow or an incandescent temperature by the operating current during the operation of said device. The upper electrode chamber is provided with a covering 4 extending to the tube part 1 surrounding the positive col-

umn, said coating being of opaque material and being, for example, a metal cap, or a cap of insulation material, or a coating of lacquer. The lower electrode chamber also has an opaque covering 5, said covering 5 having an opening 6 in the region of the glowing electrode 3, said opening 6 having a suitable cross, square, or round shape. The glowing electrode 3, visible through the opening 6, has a brilliant halo and the opening 6 serves as a window to permit the passage of the light emitted by the glowing electrode 3 and its accompanying halo. The phenomena that the color of this bright light emitted by the electrode and its halo is somewhat different than the color of the positive column, is of no practical importance as the observer gets the same light impression from both sources. When the light tube described herein and illustrated in the drawing is mounted vertically it forms an exclamation point and is useful in sign work.

It will, of course, be understood that various substitutions, modifications and changes in the forms and details of the device may be made by those skilled in the art without departure from the broad spirit and scope of the invention, for example, various other tubes and electrode chambers may be provided with similar glowing electrodes, the electrode chambers being provided with a suitably shaped window to permit the passage of the light emitted by said electrodes and the halo surrounding them.

What we claim as new and desire to secure by Letters Patent of the United States, is:

In a sign, an electric discharge device comprising a linear container, electrodes sealed therein, a gaseous atmosphere therein, an electrode chamber at each end thereof, said container having a linear shape, said electrode chambers and one end of said linear container adjacent one of said chambers being opaque, the margin of the opaque end of said container being notched, the electrode chamber adjacent the opaque end of said container having a circular light pervious window in the vicinity of the electrode mounted in said chamber, the point of said notch and the center of said circular window being in the same plane as the longitudinal axis of said container.
